UNITED STATES PATENT OFFICE

JOHANN VALERIUS, OF HEILIGKREUZ, NEAR NEISSE, GERMANY

SERIES SWITCH

Application filed February 10, 1927, Serial No. 167,263, and in Germany July 31, 1926.

This invention relates to an electric series-switch and it consists in connecting all series-circuits by contact devices, of which each one can be separately operated, to a metal ring which is connected to an interrupter-terminal of the supply circuit and adapted to be inserted into this supply circuit by means of the switch. When the supply circuit is closed by the switch, every series circuit can be closed or interrupted independently of the other series-circuits, and all or several series-circuits can be interrupted simultaneously by the switch.

An embodiment of the invention is illustrated, by way of example, in the accompanying drawings, in which

Fig. 1 shows the switch base in plan view in a section on line 1—1 of Fig. 2.

Fig. 2 is a vertical section.

Figs. 3 and 4 show each in vertical section a modified construction of a contact terminal and contact bolt.

In the base *a* two interrupter-contacts *c* and *c'* are arranged on which the circuit can be closed by a depression of a push-knob *d* in the cover *b* and carrying a contact disk *e*. The push-knob *d* is held in the circuit-closing position by means of a blade spring *g* engaging with an annular groove *f* of the knob-shaft. To release the push-knob *d* a press-button *h* has to be pushed inward which projects from a bore in the side wall of cover *b* and, when being pushed inward, spreads the blade spring *g* in outward direction so that it releases the groove *f* and the push knob *d* can jump back into the initial position by the action of a spiral spring. The leading-in wire is connected to the interrupter contact *c*, the second contact *c'* being permanently connected to a metal ring *i* which, when the push knob *d* is in the contact position, is inserted in the circuit. This metal ring *i* may be arranged in the base *a*, or in the cover *b* of the switch, as shown in Fig. 4 at *i'*. On the inner side of metal ring *i* a number of contact terminals *k* are arranged in the base *a* of the switch and consisting of bolts with nuts for clamping the wires or of hollow pins *k'* (Figs. 3 and 4) the wire being in this case passed through the bore. Every contact terminal *k*

or *k'* serves to connect one series-circuit and opposite each contact terminal a contact device is arranged which is permanently connected to the metal ring *i* or *i'* and adapted to be connected to the opposite contact terminal. These contact devices consist of screw bolts *m* with heads *n* of insulating material. The screw bolts *m* are screwed into the metal ring *i* or *i'* so that each screw bolt *m* points towards a contact terminal *k* and touches the same when it is being screwed in. The screw bolts may be horizontally, or as shown in Fig. 4, vertically directed towards the contact terminals. Each contact bolt *m* has a head *n* of insulating material which projects outwards through a bore in the cover *b* so that it can be operated to close the corresponding series-circuit.

When the head *n* is turned the corresponding contact bolt *m* is screwed in and the corresponding series-circuit is closed; when the same contact bolt is unscrewed the corresponding series-circuit is interrupted. When, however, the push knob *d* is brought into the cutting-out position, the electric connection between the supply circuit and the metal ring *i* or *i'* is interrupted and all the series-circuits are cut-out.

Instead of a push knob any switch handle of known type may be used for interrupting the supply circuit, for instance a rotary switch handle of known type. The heads *n* of the screw bolts *m* might be arranged so that these contact bolts, instead of being screwed in or out, are pushed in and out. In the latter case the contact bolts *m* are smooth pins and the insulating heads *n* are pushed outwards by the action of springs and they are secured in the switching-in position by means of a bayonet joint, so that they must be slightly turned after having been pushed in.

I claim:—

1. An electric switch comprising in combination with the cut out for the feed wire and a current distributing ring connected to said feed wire and with a number of contact devices for tapping individual circuits from the distributor ring, said contact devices consisting of connecting terminals perpendicularly fixed in the base plate of said switch,

- of screw pins in an upper portion of said switch traversing said distributor ring at right angles to the bolts of the connecting terminals, and a handle on each of said screw pins projecting from the rim of said upper part of said switch so that said screw pins can be adjusted with regard to said bolts of said connecting terminals.
2. An electric switch comprising in combination with the cut out for the feed wire and a current distributing ring connected to said feed wire and with a number of contact devices for tapping individual circuits from the distributor ring, said contact devices consisting of connecting terminals perpendicularly fixed in the base plate of said switch, of screw pins in an upper portion of said switch traversing said distributor ring at right angles to the bolts of the connecting terminals, and a handle on each of said screw pins projecting from the rim of said upper part of said switch so that said screw pins can be adjusted axially with regard to said bolts of said connecting terminals.
3. An electric switch comprising in combination with the cut out for the feed wire and a current distributing ring connected to said feed wire and with a number of contact devices for tapping individual circuits from the distributor ring, said contact devices consisting of connecting terminals perpendicularly fixed in the base plate of said switch, of screw pins in an upper portion of said switch traversing said distributor ring at right angles to the bolts of the connecting terminals, and a handle on each of said screw pins projecting from the rim of said upper part of said switch so that said screw pins can be adjusted, said contact devices consisting of connecting terminals beside said distributor ring, and of screw pins with handle traversing said distributor ring and adapted to be adjusted with regard to said connecting terminal, a resilient push button for connecting said terminals for the feeding of currents to said distributor ring, said push button having a circular groove in its stem, an oval spreading spring arranged underneath said push button and engaging with said groove of the push button stem, and a handle on said spreading spring projecting from the switch case and adapted to spread said spring when being pressed in and to release said push button.
- 55 In testimony whereof I affix my signature.
JOHANN VALERIUS.
